UNITED STATES PATENT OFFICE.

EDWARD POSSON, OF CHICAGO, ILLINOIS, ASSIGNOR OF ONE-HALF TO FREDERICK C. MAEGLY, OF CHICAGO, ILLINOIS.

GRAIN DOOR.

Application filed May 16, 1919. Serial No. 297,537.

To all whom it may concern:

Be it known that I, EDWARD POSSON, a citizen of the United States, residing at Chicago, in the county of Cook and State 5 of Illinois, have invented certain new and useful Improvements in Grain Doors, of which the following is a specification.

The purpose of this invention is to provide an improved sectional grain door in 10 which the door sections travel in guideways and are supported in operative position by brackets or hangers. The principal object of the invention is to provide a grain door comprising a plurality of relatively 15 narrow sections adapted to be supported in inoperative position above the door opening without interfering substantially with said opening. Another object is to provide a sectional grain door in combination with 20 improved means for preventing the binding of the door sections in the guideways. Still another feature is the provision of an improved guideway and connecting bracket for supporting the door sections. Still another object is to provide improved means 25 for connecting the door sections with the guideways in order to permit a free movement of the door sections while providing a grain tight closure. Other objects relate 30 to various features of construction and arrangement, which will appear more clearly hereinafter.

The nature of the invention will be understood from the following specification taken with the accompanying drawings, in which one embodiment is illustrated.

In the drawings—

Figure 1 is a vertical longitudinal section through the interior of a car showing 40 a side elevation of my improved sectional grain door in closing position;

Fig. 2 is a view similar to Fig. 1 showing the grain door in open position viewed from the interior of the car;

Fig. 3 is a horizontal sectional view on the line 3—3 of Fig. 1, showing the means 45 for mounting the supporting brackets;

Fig. 4 is a transverse vertical section taken on the line 4—4 of Fig. 2, showing 50 the door sections in open position.

Fig. 5 is a sectional view, similar to Fig. 4, showing the door sections in closed position;

Fig. 6 is an enlarged side elevation of 55 one corner of a door section, showing the

means for connecting the door section with one of the guideways;

Fig. 7 is a sectional view taken on the line 7—7 of Fig. 6;

Fig. 8 is a detailed sectional view 60 through one of the guideways taken on the line 8—8 of Fig. 4;

Fig. 9 is an enlarged elevation of one of the complementary parts of the vertical guideways;

Fig. 10 is a detailed sectional view 65 through one of the guideways taken on the line 10—10 of Fig. 9;

Fig. 11 is another detailed sectional view 70 of one of the guideways taken on the line 11—11 of Fig. 5; and

Fig. 12 shows a perspective view of two 75 of the complementary parts of the vertical guideway.

The invention is illustrated in connection with a railway car comprising a side wall 15, a floor 16, and a roof 17 carried by the transverse frame members 18. A door opening is formed through the side wall 15, and door posts 19 extend vertically along 80 each side of the door opening between the floor 20 and the frame member 21, which extends across the upper part of the door opening. The inside sheathing 22 is secured to the door posts within the car, and door 85 jambs 23 extend vertically along the inner sides of the door posts and overlap the ends of the sheathing, as illustrated in Fig. 7.

The grain door is formed of a plurality 90 of complementary door sections 25, which preferably have their body portions formed of wooden members 25^a covered by layers of sheet metal 25^b. The metal sheathing is secured to the wooden body portions of the door sections by rivets 26, and each door 95 section is provided on its inner and outer sides, at opposite sides of the center thereof, with hand-holds 27. The door sections are provided with interfitting flanges and recesses along their contacting edges for 100 forming grain-tight connections. The ends of the door sections 25 are adapted to engage guideways 28, which are secured to the door posts 19 by screws 29, and which coact with the vertical faces of the door jambs 23, 105 forming continuations of the members 23 as shown in Fig. 7. The guideways 28 are formed preferably of metal, with oppositely disposed vertical walls 30 and 31, which are 110 spaced apart to receive the ends of the door

sections 25. The walls 30 and 31 are provided with inwardly extending vertical flanges 32, which are spaced from the ends of the door sections, and which have a vertical slot 33 between them adapted to receive the guiding lugs or bolts 34, which are carried by the sections of the door. Each bolt or lug 34 has an enlarged circular head 34^a, which is adapted to travel in the under-cut groove or recess 33^a which is formed between the vertical flanges 32 and the end wall 35 of the guideway, as illustrated particularly in Figs. 6 and 7. The guiding bolts 34 are slidably mounted in cylindrical recesses 36, which extend inwardly from the ends of each door section adjacent the upper corners thereof. These recesses are formed preferably in metallic members 37, which are mounted between the opposite layers of the metal sheathing 25^b and form continuations of the wooden portions 25^a. Each of the members 34 is provided with a longitudinal slot 34^b between its ends, and this slot is engaged by one of the rivets 26, so that relative movement of each bolt 34 is permitted longitudinally of the door section, although the complete removal thereof is prevented.

The guideways 28 are formed in complementary parts, as illustrated particularly in Figs. 2, 9, and 12. The inner wall 30 of each part is provided with a rectangular notch or recess 38 at one end and a corresponding rectangular projection 38^a at the other end, the projection at one end of one part being adapted to engage the recess at the adjacent end of the other part, thereby preventing relative lateral movement of the complementary parts of the guideways.

Relative movement of the complementary parts of the guideways transversely of the car is prevented by securely fastening the guideways to the vertical faces of the door posts 19 by means of screws 29, previously referred to. These screws engage apertures 29^a, which are formed through the inner walls 30 of the guideways and through the projecting tongues or flanges 39 which extend from the walls 30 toward the ends of the car and underlie the door jambs 23 which are engaged. The edges of the outer walls 31 of the guideways are provided with notches 40 in alignment with the holes 29^a through the walls 30 to permit the insertion of the screws 29.

The upper section of each guideway is provided with an angularly disposed part 41 which serves as a bracket to support the door sections when they are in inoperative position adjacent the roof of the car. A short distance below the upper edge of the door opening each guideway is provided with an outwardly extending plate or flange 42, which is, in effect, a continuation of the inwardly extending flange 32 previously described.

The projecting portion of the outer wall 31 is carried out in an inclined direction along the edge of the plate 42, forming a flange 43 adapted to engage the lower edges of the door sections as they pass out of or into the vertical portions of the guideways. The guideway for the bolts 34 extends upwardly beyond the plate 42, is inclined upwardly and toward the center of the car from the point 44, and has an upward projection at the point 45. From the point 45 the slot 33, between the flanges 32, extends upwardly and inwardly toward the center of the car, being closed at its end by a flange 46. The flange 46 extends downwardly below the slot 33 to engage the uppermost door section, as shown in Fig. 4, and each flange 46 is reinforced by a web 47. The innermost ends of the guideways at opposite ends of the door opening are prevented from spreading longitudinally of the car by a tie-rod 49, which extends through the ends of the guideways and is engaged by nuts 50. Inclined braces 51 extend from the ends of the tie-rod to the side walls of the car, where they are secured in position by bolts 52. The end walls of the brackets are extended upwardly as plates 53 terminating in transverse flanges 54 adapted to seat against the side plate and transverse members 18 of the car. The brackets are secured by bolts 55 extending through the side plates, and they may also be secured to the members 18.

In passing the door sections from the vertical portions of the guideways to the brackets 41, the heads 34^a of the guiding bolts travel in the guides or recesses 29 between the flanges 32 and the end walls 35 of the guideways until the points 45 are reached, where the bolts pass over the humps in the guideways, and then rest in the substantially horizontal or slightly inclined portion which forms the bracket 41. After passing over the humps 45, the bolts are prevented from returning accidentally to the vertical portion of the guideway, and the door section is thus held in inoperative position adjacent the roof of the car. As the bolts 34 pass upwardly beyond the points 44 the lower edges of the door sections automatically pass inwardly between the plates 42 and above the inclined guide flanges 43, which form guide chutes for the door sections. When it is desired to lower the door sections they are pushed upwardly to elevate the bolts 34 over the humps 45, and the lower edges are guided into position above the guide flanges 43, whereupon each door section automatically falls to its proper door-closing position, with the ends of the door section proper extending between the walls 30 and 31 of the guideways to form a grain-tight closure. To prevent binding of the door sections in the guideways the ends of the door sections

terminate short of the flanges 32, so that tilting of the door sections will not cause a binding thereof between the flanges 32 carried by the opposite guideways. The clearance between the flanges 32 and the ends of the door sections permits longitudinal relative movement of the door sections with respect to the guideways, and during this movement the door sections slide on the 10 guiding bolts 34, which are capable of relative movement longitudinally of the door sections, as previously described. The heads 34^a of the bolts 34 loosely engage the vertical undercut grooves 33^a of the guideways, so that binding of the heads 34^a in these grooves is prevented. This construction has the advantage that the removal of the door sections from the car is positively prevented, while at the same time the free vertical 20 movement of the door sections in the guideways is permitted without binding. This invention makes it possible to use a large number of complementary door sections of relatively narrow width, so that the head 25 room or space beneath the upper frame member 21 of the door opening is not interfered with by the depending door sections carried by the supporting brackets.

This invention has the advantage that the 30 door sections embodied in the grain door may be raised or lowered from the outside or from the inside of the car, and this may be done when the car is empty during the process of loading, after the loading of the 35 car is completed or to permit a person to enter the car for the purpose of inspecting its contents. When elevated into the supporting brackets, the door sections do not interfere with the door opening, so that they 40 are not liable to be damaged by the loading or unloading of the car or by the movements of the goods within the car during its travel. By constructing the door sections with wooden fillers and metal jackets, they are 45 made as durable as metal door sections, but they have the advantage of being much lighter in weight and capable of being more easily operated by one man. These door sections can be attached to a door-way of 50 any height or width, which is an advantage not present in other grain doors. All of the sections are alike, so that if any of the sections becomes broken it can be immediately replaced by another section of the same design which may be inserted anywhere in the 55 series of door sections.

Although I have shown and described a certain embodiment of the invention for purposes of illustration, it will be understood that it may be constructed in various other forms without departing from the scope of the appended claims.

What I claim is:

1. The combination in a railway car, of a 60 wall having a door opening therein, guide-

ways along the opposite edges of said door opening, a plurality of complementary door sections, and lugs engaging said guideways and movably mounted on said door sections for longitudinal travel in the planes 70 of the door sections.

2. The combination in a railway car, of a wall having a door opening therein, guideways along the opposite edges of said door opening, a plurality of complementary door sections, said door sections being recessed inwardly from their ends, and lugs slidably mounted in said recesses and engaging said guideways. 75

3. The combination in a railway car of a wall having a door opening therein, a plurality of complementary door sections, guideways extending along the vertical edges of said door opening throughout the height of said opening to receive the ends 80 of said door sections, supplementary guideways extending vertically adjacent said first named guideways, and lugs movably mounted on said door sections and engaging said supplementary guideways, said first named 85 guideways terminating adjacent the upper part of said door opening in transverse brackets adapted to support all of said door sections in close proximity to the upper part of said door opening whereby all of 90 said sections are capable of being moved from said brackets into said vertical guideways by an operator located on the outside of said car. 95

4. The combination in a railway car of a wall having a door opening therein, slotted guide members extending vertically along the edges of said door opening, a plurality of complementary door sections, lugs carried by the ends of said door sections and 100 engaging the slots in said guide members, said lugs terminating in parts of greater width than the said slots, and flanges formed integrally with said guide members 105 and projecting therefrom at the sides of 110 said slots to form guideways to receive the ends of said door sections.

5. The combination in a railway car, of a wall having door openings therein, slotted guide members extending vertically along the edges of said door opening, a plurality of complementary door sections, lugs carried by the ends of said door sections and 115 engaging the slots in said guide members, said lugs terminating in parts of greater width than said slots, and flanges carried 120 by said guide members to receive the ends of said door sections, said flanges terminating adjacent the upper part of said door opening in outwardly directed chutes adapted to guide the lower edges of said door sections, said grooved guide members being continued upwardly from said flanges and extended transversely of the car to form 125 supporting brackets. 130

6. The combination in a railway car, of a wall having a door opening therein, a plurality of complementary door sections, door posts extending along the vertical edges of said door opening, vertical guide members secured to said door posts and having walls adapted to coact with parts carried by said door sections, said guideways being formed in complementary sections having interlock-

ing parts at their ends, flanges extending outwardly from said guide members and secured to said door posts, and door jambs overlying said flanges and secured to said door posts. 10

In testimony whereof, I have subscribed 15
my name.

EDWARD POSSON.
